UNITED STATES PATENT OFFICE.

LIONEL CLAUDE NOBLE, OF AMSTERDAM, NEW YORK, ASSIGNOR TO STEPHEN SANFORD & SONS, INC., OF AMSTERDAM, NEW YORK, A CORPORATION OF NEW YORK.

DESIGN FOR A RUG.

47,141.

Specification for Design.

Patented Mar. 23, 1915.

Application filed November 21, 1914. Serial No. 873,419. Term of patent 3½ years.

To all whom it may concern:

Be it known that I, LIONEL CLAUDE NOBLE, a subject of the King of Great Britain, residing at Amsterdam, in the county of Montgomery and State of New York, have invented a new, original, and ornamental Design for a Rug of Small Sizes, of which the following is a specification, reference being had to the accompanying drawing, forming part thereof.

The drawing illustrates one-quarter of a rug showing my new design, the remaining three quarters being duplicates thereof.

I claim:

The ornamental design for a rug, as shown.

LIONEL CLAUDE NOBLE.
